RECEPTACLE AND CLOSURE

William Lockhart, Cleveland, Ohio, assignor to
Cornell Securities Corporation, Cleveland,
Ohio, a corporation of Delaware

Application May 2, 1935, Serial No. 19,439

3 Claims. (Cl. 220—61)

My invention is an improvement in metallic receptacles and closures therefor and relates more particularly to a clamping ring for removably clamping the cover on the receptacle in fluid tight sealed relation thereto.

One of the objects of the present invention is a split channelled clamping ring comprising a plurality of sections pivotally connected together and having means bridging the ends of adjacent 10 sections for contracting the ring as a unit to seal a cover on a receptacle.

Another object of the invention is to provide such a clamping ring with independently operable link and lever connections at spaced intervals 15 about the ring, such as at substantially diametrically opposite points on the ring circumference.

A further object is to construct a clamping ring comprising two or more sections, and connecting the adjacent ends of adjacent sections with suitable means for drawing the ends together to seal a 20 cover on the receptacle in fluid tight relation, whereby different degrees of closing pressures may be applied to the cover.

Other objects and advantages of my invention 25 will become apparent from the following description of one embodiment thereof, reference being made to the accompanying drawing in which like reference characters are employed to designate like parts throughout the same.

30 In the drawing:—

Figure 1 is a top plan view of an embodiment of my invention and shows the same applied in use;

Figure 2 is an enlarged section taken on line 35 2—2 of Figure 1;

Figure 3 is a fragmentary view of the ring applied in use and shows the same contracted;

Figure 4 is a fragmentary view of one link and lever connection and shows the adjacent ends of 40 adjacent ring sections separated in ring expanded position. In this view the connection employed is used to finally contract the ring;

Figure 5 is a view similar to that of Figure 3 and shows the substantially diametrically opposite link and lever connection for applying the initial contracting forces to the ring sections;

Figure 6 is a view similar to that of Figure 4 and shows the longer link connection of Figure 5 in ring expanded position;

Figure 7 is a view taken in the direction of line 50 7—7 of Figure 3;

Figure 8 is a sectional view taken on line 8—8 of Figure 3;

Figure 9 is a section taken on line 9—9 of 55 Figure 7; and,

Figure 10 is an elevation taken in the direction of line 10—10 of Figure 5.

Referring now more particularly to the drawing, the barrel or drum is indicated at 1. The upper open end of the container is formed with a peripheral bead 2. A cover 3 comprising a cupped or depressed head, having a peripheral upwardly and outwardly extending flange 4, is supported by the bead 2 in such a manner that the cupped portion of the head or cover may be telescoped 10 for a short distance within the open end of the drum, as illustrated in Figure 2. It will be noted that a portion of the flange 4 is of substantially arcuate cross section to conform with the approximate curvature of the upper surface of the 15 bead. A packing 5 consisting of an annulus of any suitable packing material, such as flexible rubber tubing or cork, is interposed between the flange 4 and the bead 2.

According to the present invention I have provided an improved means for removably securing the cover on the drum or receptacle to effect a fluid tight seal therebetween by exerting a substantially uniform and firm pressure along the cover flange and bead in a direction substantially 20 parallel to the longitudinal axis of the drum.

Such means preferably includes a transversely split channelled clamping ring 6 of substantially U-shaped cross section and which is capable of being expanded and contracted by suitable means. In the form illustrated the upper and lower flange and bead engaging walls respectively of the ring converge slightly toward the outer diameter of the ring and engage the cover flange and bead of the container to press the same together tightly when the ring is contracted. However, it is to be understood that the ring and receptacle open end may be so designed that the cover will be pressed into a tight seal with a shoulder formed at the receptacle open end when the ring is expanded. That is, instead of the receptacle being formed with a rolled bead 2, the open end may be formed with an annular shoulder and an annular channel for receiving an expander type ring, a packing ring and the cover.

By contracting the type of clamping ring herein illustrated, the cover flange will be pressed tightly against the packing 5 and the supporting bead 2 under a substantially vertical pressure.

In further carrying out my invention the ring 6 is composed of a plurality of connected sections, preferably two, 7 and 8. Adjacent ends 9 and 10 of the respective sections 7 and 8 may be movably connected together with a link and lever mechanism 11 and 12 respectively, the lever

12 having pivotal connection with the end 10 as at 13. One end of the link 11 is pivotally connected with the end 9 of the ring section 7 as at 14 while its opposite end is pivoted to the lever 5 12 at 15.

The opposite ends of the ring sections 7 and 8 are likewise movably connected together with a link and lever mechanism 16 and 17, the lever 17 being pivoted to swing outwardly of the end 18 of 10 the section 8 at 19, while the shorter link 16 pivotally connects the lever 17 at 20 with the adjacent end 21 of the section 7 as at 22. For convenience 15 of operation, the levers 12 and 17 are both pivoted to the opposite ends of the ring section 8, and when they are swung to contract the ring and bring the sections together, they will move toward each other and the periphery of the section 8. To expand the ring the levers are thrown outwardly as indicated in Figures 4 and 6.

20 Suitable retainers 23 and 24 are welded to the ring section 8 and are positioned to receive the handle ends of the respective levers 17 and 12 and to retain them in closed position.

It is to be noted that greater leverage is provided through one of the connections as at 16 and 17. This is desirable because in accordance with my invention the ring is contracted initially to fix the cover firmly in place upon the open end of the receptacle by one link and lever connection, as at 11 and 12, and is then further contracted to apply even greater closing forces to the cover to seal the same in fluid tight relation to the receptacle. It is found that, while the levers are preferably operated independently, that is, lever 12 is first swung to the position in Figure 5 to close the ring, and lever 17 is subsequently swung to the position in Figure 3, these levers may be operated simultaneously or in the reverse order. But greater ease of operation is had if the levers are operated in the preferred manner described.

Each of the operating levers and the associated links are arranged to operate on the upper surface of the ring, which leaves the assembly free 45 of objectionable obstructions when it is desired to store the drums in close quarters. Furthermore, the drums may be rolled horizontally without interference from projections on the ring.

While I have described the illustrated embodiment of my invention in some particularity, obviously many others will readily occur to those skilled in this art, and I do not, therefore, limit myself to the precise details shown and described but claim as my invention all embodiments, variations and modifications thereof coming within the scope of the appended claims.

I claim:

1. A device for removably clamping a cover on the open end of a metallic receptacle including a channeled clamping ring split transversely at a plurality of points about its circumference and having portions engaging the cover and the receptacle to press the same together when the ring is contracted, and means for contracting the ring including levers pivoted to the ends of one ring section and swingable outwardly of the ring, 10 links pivotally connected with the adjacent ends of an adjacent section and with said levers, one of said operating links and levers having a greater leverage ratio than said other cooperating link and lever whereby said ring may be contracted sufficiently to maintain a cover in fixed position on the receptacle by operating one of said levers, and to apply a secondary sealing pressure to the cover by operating the other of said levers.

2. A device for removably clamping a cover on 20 the open end of a metallic receptacle including a channeled clamping ring split transversely at a plurality of points about its circumference and having portions engaging the cover and the receptacle to press the same together when the 25 ring is contracted, and means for contracting the ring including levers pivoted to the ends of one ring section and swingable outwardly of the ring, links pivotally connected with the adjacent ends of an adjacent section and with said levers, one 30 of said links being of greater length than said other link whereby said ring may be contracted sufficiently to maintain a cover in fixed position on the receptacle by operating one of said levers, and to apply a secondary sealing pressure to the 35 cover by operating the other of said levers.

3. A device for removably clamping a cover on the open end of a metallic receptacle including a channeled clamping ring split transversely at a plurality of points about its circumference and 40 having portions engaging the cover and the receptacle to press the same together when the ring is contracted, and means for contracting the ring including levers pivoted to the ends of one ring section, links pivotally connected with 45 the adjacent ends of an adjacent section and with said levers, one of said operating links and levers having a greater leverage ratio than said other cooperating link and lever, whereby said ring may be contracted sufficiently to maintain 50 a cover in fixed position on the receptacle by operating one of said levers, and to apply a secondary sealing pressure to the cover by operating the other of said levers.

WILLIAM LOCKHART.
